LONG TUBE VERTICAL EVAPORATOR

Ralph E. Bergstrom, Chicago, Ill., assignor to Whiting Corporation, a corporation of Illinois

Application January 4, 1954, Serial No. 401,874

5 Claims. (Cl. 159—46)

My invention pertains generally to evaporators, and more particularly to a long tube vertical evaporator having both liquid heating tubes and liquid evaporating tubes disposed within a single shell or body.

Long tube vertical evaporators generally utilize an upright tube bundle enclosed by a shell into which a condensable heating fluid, usually steam, is introduced. The liquid to be evaporated may be first passed through an externally disposed heater and then into the tube bundle where boiling and evaporation occurs, the vapors so generated being discharged into a vapor head above the tube bundle. In other instances, the necessary heating of the liquor is accomplished within the evaporating tubes, eliminating the external heater, but requiring a larger tube bundle in the evaporator body. Ordinarily a baffle is mounted in the vapor head above the tube bundle to deflect into a suitable drain any liquid particles emerging from the evaporating tubes. It has been found in operation, however, that a certain amount of the liquid collected on the lower surface of the baffle will fall back into the evaporating tubes and there create undesirable changes in liquor concentration.

One of the important objects of my invention is the provision of a long tube vertical evaporator of greater efficiency which incorporates within a single shell a set of heater tubes and a set of evaporating tubes, each set of tubes being adapted for operation in series at optimum velocity.

Another important object of my invention is the provision of a long tube vertical evaporator and heater unit which occupies less floor space than that ordinarily required and which renders unnecessary a portion of the accessory equipment normally disposed externally to the evaporator.

A further important object of my invention is the provision of a long tube vertical evaporator which is more efficient than the type now in general use, which is less costly, and which reduces the amount of fall back of liquor into the evaporating tubes from the baffle.

Additional objects of my invention reside in various sub-assemblies and the relation and proportions existing between the various components, all of which are fully explained in the following description and illustrated in the appended drawing, in which:

Fig. 1 is a schematic elevation of a long tube vertical evaporator incorporating my invention.

Fig. 2 is a horizontal cross section taken on the line 2—2 of Fig. 1.

In brief, my evaporator employs a generally cylindrical tube bundle mounted in a shell. The center set of tubes in this bundle is employed solely for heating the liquor, suitable connections being provided for causing the incoming liquor to flow up one portion of this set of heater tubes and down the other portion. Upon emergence from the heater tubes the liquor is distributed to the evaporator tubes in which it is vaporized, these latter tubes being arranged circumferentially around the heater tubes. A

2

baffle is provided in the vapor head and extends over the upper ends of the tubes.

To obtain efficient liquor heating, the velocity of liquor flow in the heater tubes must be substantially greater than the velocity of liquor flow in the evaporating tubes. It is therefore essential that the total cross-sectional area of the heater tubes employed to carry the liquor in one direction be less than half the total cross-sectional area of the evaporating tubes, and better results will be obtained if this ratio is further reduced, as for example, 1:5, 1:100 or 1:250. By properly selecting this ratio, both the heater tubes and the evaporating tubes may be operated at optimum velocity, thereby substantially improving the efficiency of the device. Heat losses by radiation may also be reduced in comparison to some conventional evaporators, since the total exposed area of my shell is less than the total exposed area of a conventional shell plus the exposed area of the conventional heater and interconnecting piping and accessories. Furthermore, the rate of liquor fall back into the evaporating tubes is reduced since there are no evaporator tubes disposed below the center portion of the baffle.

Referring to the drawing, I have illustrated a long tube vertical evaporator having a shell 10 adapted for operation in an upright position. Arranged around the upper portion of the shell 10 and communicating therewith is a catchall body 11 having a steam inlet 12. The catchall is generally cylindrical in shape and may be provided with a drain 13 near its lower extremity. The passageway 14, which interconnects the catchall 11 with the shell 10, is disposed near the upper extremity of the catchall and preferably above the level of the steam inlet 12. A condensate drain 16 is provided near the lower extremity of the shell 10.

An upper tube sheet 17 and a lower tube sheet 18 are sealed to opposite ends of the shell 10. A set of upright heater tubes 19 extends through the center portions of the tube sheets 17 and 18 and are surrounded by circumferentially arranged evaporating tubes 21, which also extend through the sheets 17 and 18. A dished bottom 22 is sealed to the lower end of the shell 10 and the lower tube sheet 18, providing interconnection between all of the evaporator tubes 21. A liquor inlet 23 may extend through the dished bottom 22 and communicate with half of the heater tubes 19. A cap 25 is sealed to the upper tube sheet 17 across the upper ends of all the heater tubes 19 and may additionally be utilized to support a baffle 24 extending laterally over the evaporating tubes 21. A vapor head 26 having a drain 27 extends around the baffle 24 and is sealed to the catchall 11 in conventional manner.

In operation, steam is introduced into the shell 10 through the steam inlet 12. The liquor to be evaporated is introduced through the liquor inlet 23 and flows upwardly through approximately one-half of the heater tubes 19 into the cap 25, then downwardly through the remaining heater tubes 19 into the bottom 22. From this all the liquor rises in the evaporating tubes 21 where evaporation takes place, the vapor being discharged from the open upper ends of the evaporating tubes 21 against the baffle 24. As previously noted, it is essential to efficient operation that optimum velocity of liquor flow be maintained in the heater tubes 19 and in the evaporating tubes 21, the former velocity being substantially greater than the latter. This I accomplish without the aid of pumps or other accessory equipment by limiting the ratio of cross-sectional area of the heater tubes employed to carry liquor in one direction to the total cross-sectional area of the evaporating tubes. It is essential that this ratio be not greater than 1:2 and preferably should be less than 1:10, that is, the total cross-sectional area of the heater tubes 19 employed to conduct the incoming

liquor upwardly (when the two sets of heater tubes are of equal cross sectional area) should be less than 1/10 the combined cross-sectional area of the evaporating tubes. For all practical purposes the upper limit of the acceptable range of the ratio may be regarded as being one in which the total cross-sectional area of the two sets of heating tubes is substantially less than one-quarter of the total cross-sectional area of the evaporator tubes.

By obtaining an adequately high velocity in the heater tubes the formation of a film resistant to heat transfer along the internal surface of the tube is inhibited. In addition, boiling of the liquor within the heater tubes is virtually eliminated. By virtue of the improved efficiency of my device, less total heating surface is required than that conventionally considered essential for a given rate of evaporation. Conversely, with the same heating surface greater evaporator capacity can be obtained by utilizing the structure described.

It will be noted that the cap 25 is centrally disposed with respect to the baffle and that the evaporating tubes 21 are disposed below the peripheral portion of the baffle 24. The rate at which liquid collected on the lower surface of the baffle 24 falls back into the evaporating tubes varies directly with the distance the liquor must travel along the baffle to reach the extremity of the baffle. Since the central portion of the baffle 24 is not employed for this purpose, the rate of liquor fall back into the evaporating tubes 21 is reduced.

By utilizing my invention the need for an external heater is obviously limited. This also eliminates the exposed piping required to connect the heater with the evaporator body and with a source of steam, which in turn not only reduces the cost and the minimum floor space required but also reduces the total exposed surface area through which heat may be lost by radiation to the atmosphere.

In comparison with conventional evaporators not using an external heater, I can reduce the total number of tubes required to accomplish the work and thereby use a smaller shell and less floor space. In addition, the initial cost is also reduced, or for substantially the same cost as a conventional evaporator, increased capacity may be obtained.

These advantages may be illustrated by a specific problem. For example—assume it is desired to heat 110,440 pounds per hour of liquor having 24% total solids and a specific heat of 0.84 from 20° F. to 224° F. using steam at 246° F. or about 13 pounds gauge pressure, and to evaporate 26,900 pounds from the liquor. Using 2 inch O. D. steel tubes 27 feet long with a wall thickness of 0.125 in., and arranging the heating tubes in two passes would require 22 tubes in the heating portion and 468 tubes in the evaporating portion, or a total of 490 tubes. A conventional evaporator without a heater, using identical tubes, would require 580 tubes to accomplish the same work.

The arrangement described and illustrated constitutes an embodiment of my invention, but it should be understood it may be altered in various ways as required by circumstances. For example, any number of passes may be employed in the heater tubes 19 by suitably arranging the cap 25 and providing the necessary connections at the

lower-ends of the tubes 19. It is also contemplated that the set of heater tubes 19 may be disposed in positions other than the central portion of the tube bundle. The ratios of cross-sectional area between the heater tubes 19 and the evaporating tubes 21 may be obtained by control of the number of tubes employed, or by the internal diameter of the tubes, or both, as required by circumstances.

I claim:

1. An evaporator comprising a shell, means for passing a heating fluid into the shell, two sets of heating tubes and one set of evaporating tubes within the shell, the total cross-sectional area of the two sets of heating tubes being substantially less than one-quarter the total cross-sectional area of the evaporating tubes, a vapor head sealing the top of the shell and a bottom sealing the lower end of the shell, means at the top of said tubes establishing communication between the two sets of heating tubes and other means at the top of said tubes establishing communication between the evaporating tubes and the vapor head, a liquid inlet at the bottom of one set of said heating tubes and means at the lower ends of said tubes establishing communication between said bottom and the other set of heating tubes and between the evaporating tubes and said bottom, whereby liquid introduced through said inlet will flow at relatively high velocity up through said first set of heating tubes and down through said second set and thence upwardly at relatively low velocity through said set of evaporating tubes.

2. The structure defined in claim 1 in which the two sets of heating tubes are positioned substantially centrally within the shell and are surrounded by the set of evaporating tubes.

3. The structure defined in claim 1 including a baffle mounted on the means at the top of the tubes establishing communication between the two sets of heating tubes and extending over and spaced from the upper ends of the evaporating tubes for facilitating separation of vapor from liquor in fluid impinging against said baffle.

4. The structure defined in claim 1 in which the total cross-sectional area of each set of heating tubes is less than one-tenth the total cross-sectional area of the evaporating tubes.

5. The structure defined in claim 1 including a generally horizontal baffle disposed above the tubes and extending radially over and spaced from the upper ends of the evaporating tubes for facilitating separation of vapor from liquor in fluid impinging against said baffle.
